CONTAINER AND CONTAINER
MANUFACTURE

Albert H. Lockwood, Monroe, Mich., assignor to
Consolidated Paper Company, Monroe, Mich.,
a corporation of Michigan

Application May 13, 1939, Serial No. 273,383

1 Claim. (Cl. 229—39)

This invention relates to packaging, especially of flowable material.

This invention has utility when incorporated in sheet stock packaging, assembly into receptacle form, charging of said receptacle, and sealing the receptacle as a holder for said charge.

Referring to the drawing:

Fig. 1 is a distributed plan view of sheet stock in blank-out form cut and scored for folding into a container;

Fig. 2 is a side view on an enlarged scale of the completed, closed and sealed container as formed from the blank of Fig. 1;

Fig. 3 is a section on the line III—III, Fig. 2, showing the holding form for receiving the container or carton, the contents being absent;

Fig. 4 is a plan view of the container top with the inner minor or not-meeting flaps folded inward and one of the major flaps folded therewith, leaving but the one major flap and its supplemental or secondary flap therewith;

Fig. 5 is a fragmentary view from the line V—V, Fig. 4, showing the application of adhesive to the major flap as carrying the supplemental flap and the two major flaps in partially open position ready to have the terminus of the simple major flap inserted upon the other flap adjacent the supplemental flap portion;

Fig. 6 is a plan view of the container end or top as in closed position; and

Fig. 7 is a section on the line VII—VII, Fig. 6, showing the interfitting assembly of the flaps as sealing the container.

Sheet stock may have a carton form comprising side walls 1, 2, 3, 4. Extension 5 may overlap the edge of the side wall 1 and be connected thereto with staples 6 (Fig. 2). The side 4 has end or bottom extension 7. The side 3 has extension 8 adapted to be assembled with flap 7 by staples 9. From the side 1 minor flap 10 is similar in extent away from the side 1 as the minor flap 8. This flap 10 is anchored upon the minor flap 8 and the major flap 7 by anvil stitching or clinched staples 11. From the minor side 2 there is minor flap extension 12 similar to the extension 10 and opposite thereto. This extension 12 in the set-up is connected by attaching means which may even be in this overlapping portion supplemented by adhesive or solely by adhesive, but is herein shown as reinforced by anvil stitching or clinched staples 13. There is thus produced minor flaps on three sides of the end or bottom which has major single ply portion 1.

Opposite terminus remote from this closed sealed bottom comprises major similar flap por-

tions 14, 15, from the respective sides 4, 3, and intermediate minor similar length flap portions 16, 17, from the respective sides 2, 1. In the tubular set-up of the container, these four flap portions remote from the closed end 7 may protrude beyond form 18 in which the container may be inserted for charging.

Before this insertion, or even before blanking in the handling of some stocks, it may be in order to apply thereto a surface treatment or coating 19. This might be a stain resistant or waterproofing material. In practice, especial value is found in a coating sufficiently adherent to be retained with the carton as formed, but which in the instance the charge be of plastic body especially with adherent or sticky tendencies, such may, in satisfying the adherence of the contents, isolate such contents from the container. Experience hereunder along such line is in packaging bituminous material of viscous or similar plastic and compounds thereof, say with fiber, asbestos, body forming materials. In the instance wherein asphalt is hot poured or without loading or other material therewith, this coating 19 may efficiently protect the container walls therefrom as to stain or attack, while in the instance of removal of the container it may be readily severed from the contents. In this charging of the container, say with flowable material, there is tendency to bulge or spread the sidewalls, especially in a material which may be of a higher temperature at the filling or pouring and which has a solidifying or less flow rate after charging. To this end, the form 18 may prevent this bulging or deformation of the container at the charging.

The flaps 16, 17, may be folded inward and the flap 15 folded thereon. Glue 20 may be on the flaps 16, 17, 15, and the under side of the flap 14. In the efficient carrying out of the invention herein, the flap 7, which is of approximately full bottom extent for the container is an extension of the side 4 beyond that of the extent of the minor flaps 10, 8, 12, from the respective sides 1, 3, 2. This leaves a reentrant portion 21 from which may be cut out small similar portions 22 and somewhat larger portions 23, leaving a major extent portion 24 having score portions to leave similar terminal flaps 25. This portion 24 is mounted on the flap 14 by anvil stitching or clinched staples 26 in such spacing from the side 4 as to clear the portion 5 as the flap 14 is folded toward the flap 15. The attaching means or row of staples 26 is sufficiently spaced from the longer free side of this flap 14 as to spread there-

from to leave V-opening 27, in which further adhesive 20 may be introduced by brush 28. There is thus provided since the portion 15 has its free end 29 thrust in this V-opening 27 an interlock relation for this supplemental flap portion 24 to 10 adhere in parallelism as an additional ply portion over the flap 15.

In view of the mass as loaded into the package, efficient holding may be effected even beyond that of adhering material or glue. In the instance the charge be at a temperature, say of molten bituminous matter or asphalt, the reaction from this temperature may be not only upon the coating 19 to insure isolation from the container body proper but may as well be a further 15 reaction with the glue in fixing and accelerating such as an efficient adhesive. The flaps 25 may be brought into position with staples 30.

These flaps 25 may be especially designed or colored for contents or partial identification beyond that of printed marking. The effectiveness of this container holding as against handling, even of heavy charges say up to 50 pounds or more, is insured due to the efficient holding even by stapling alone, although there may be the 20 additional efficiency as against seepage or sifting out of fine granular or flow type of material in the event of handling thereof.

In the practice hereunder, when the contents to be handled be such material as hot asphalt at the time of packaging, there may be this coating 19 and the supplemental anchoring by staples 9, 11, 13, 26. However, the final closing may omit further stapling 30 and have adhesive solely on the portion or section 24 and its flaps 25. Accordingly, at the closed down position (Fig. 7) 30 these flaps 25 may then be thrust down into the container or form 18 (Fig. 3) with the pressure of the contents thrusting the walls 1, 2, there-against and the form holding against bulging. 40

This adhesive sealing should be sufficient. However, on package removal, should such not be acceptable the additional staples 30 may then be added. By omitting the adhesive or limiting 5 the adhesive solely to this portion 24 and its flaps 25, there may be more ready opening up of the container for access to the contents.

The closure herein has particular advantage wherein water-proofed stock is used. In the use of a water-proofing composition having a paraffin and rosin base, the heat of the contents so reduces the viscosity of the water-proof coating that such is absorbed into the stock, thereby providing an outer surface susceptible of adherence with the use of an adhesive. An effective adhesion of the interfitting parts is complete under the invention herein within a space of ten to fifteen minutes.

What is claimed and it is desired to secure by 20 United States Letters Patent is:

A closure for a package embodying a pair of opposing flaps foldable in operative position to face contacting relation substantially in a common plane with free edges adjacent, a flap extension on a first of the flaps, said extension having one end anchored to the outer side of the first flap rearwardly of the free edge thereof and having its other end projecting toward the second flap and beyond the free edge of the first flap to provide with said first flap a V-way for receiving the free edge of the second flap, the free edge of the second flap, when positioned in said V-way, overlapping the free edge of the first flap, and the flap extension overlying and overlapping the free edges of both the first and second flaps, said flap extension having supplemental flap portions secured to each end thereof which in their operative position are secured to the adjacent sides of the package.

ALBERT H. LOCKWOOD.
